BREATHER CAP

Willis H. Risse, Flossmoor, Domenic P. Tortorici, Chicago, and Raymond G. Bennett, Olympia Fields, Ill., assignors to Novo Industrial Corporation, New York, N.Y., a corporation of New York

Filed Feb. 25, 1963, Ser. No. 260,436

3 Claims. (Cl. 55—417)

This invention is in the field of breather caps for use on internal combustion engines and is specifically concerned with a cap which will prevent reverse flow, meaning flow out of the crankcase, but at the same time will provide free normal flow of air into the crankcase through the filter element of the cap.

A primary object of the invention is a breather cap specifically constructed for what is commonly referred to as a closed system for the crankcase.

Another object is a breather cap for use on an internal combustion engine having a self-contained check valve to prevent reverse flow.

Another object is a breather cap which would allow the crankcase to be pressurized.

Another object is a breather cap specifically constructed to provide the proper flow of air at certain speeds.

Another object is a breather cap specifically constructed for anti-smog conditions.

Another object is a closed crankcase ventilating system. Other objects will appear from time to time in the ensuing specification and drawings in which:

FIGURE 1 is a side view, partly in section, of the breather cap;

FIGURE 2 is a bottom view of FIGURE 1.

FIGURE 3 is a diagrammatic of the engine system.

In FIGURE 1, we show a so-called breather cap generally designated 10 which has a cap type formation with a closed top 12 surrounded by closed depending sides 14 and a generally open interior 16 which opens on the bottom. The cap itself is made of an outer cap or shell 18 which has a cylindrical exterior and is shown with a generally flat top 20 joined integrally to the exterior with the sides or exterior terminating at a lower edge 22. The interior of the cap may be formed by a shell or interior 24 which turns outwardly at its lower edge, as at 26, into a flange which extends out to the lower edge 22 of the exterior or cap. It will be noted that the lower edge of the cap may be crimped around the outstanding edge or flange 26, as at 28. Flange 26 may have a plurality of openings, shown in this case as round, as at 30, although these may be slots disposed radially or circumferentially or otherwise. In any event, these openings, in effect, provide an inlet to the annular filter material 32 which is enclosed between the outside cap and inner body or shell.

The top of the inner body or shell is shaped to conform generally to the outside cap and is turned over or extends inwardly in spaced relation to the top surface 20 and terminates in a central opening 36 or the like. While the openings 30 at the lower edge of the filter material may be considered the inlet, the opening 36 within the body of the cap opening into the central cavity or area 16 may be considered the outlet. We use the expression that they may normally be considered the inlet and outlet because under certain conditions of reverse flow in normal breather caps, the situation is reversed.

Over the outlet opening 36, we position a non-return or check valve 38 which may take the form of a bale or support 40 having three or any number of legs 42, which extend upwardly and are suitably shaped to pass through openings in the flat portion 34 of the inner shell. Each such leg may be turned over and extended out-

2

wardly, as at 44, above the flat surface 34 so that, in effect, the bale is rigidly mounted. A central depression 46 may be provided in the center of the bale which serves as a pilot mounting for a suitable spring 48, shown in this case as a coil spring. The spring, as shown in FIGURE 1, is under a certain amount of preload and biases a valve disk 50 upwardly over the opening or outlet 36. It will be noted that we provide a downwardly extending bead 52 around the opening which will function as a seat. Also, it will be noted that the diameter of contact of the spring 48 with the disk is somewhat less than the diameter of the valve seat or bead 52. This means that the disk should be of a neoprene or similar type material which will adjustably conform itself to the differential loading caused by this offset relationship.

In FIGURE 3, we have diagrammatically shown an engine 54 in which the crankcase 56 is connected by a return line 58 to the inlet 60. The return line may be controlled by a valve structure, designated generally 62, which may be the same or somewhat like conventional return flow crankcase ventilating valves now on the market, such as shown in U.S. Patent No. 3,105,477, issued October 1, 1963. The return line may be connected below the air cleaner 64 to the inlet manifold as shown, or in any suitable manner, so that the crankcase vapors will be fed back to the inlet. The fill tube for the crankcase, generally designated 66, has the breather cap 10 mounted thereon. The result is that when the crankcase 56 is pressurized or at a pressure higher than atmospheric, the breather cap will prevent crankcase vapors from exhausting out the fill tube. This is particularly true at high engine speeds. Since the manifold vacuum is the least at high engine speeds, the pressure differential through the return line 58 will otherwise be at a minimum. Thus, a pressure somewhat greater than atmospheric may build up in the crankcase. It is then desirable to prevent crankcase vapors from escaping through the fill tube.

The use, operation and function of our invention are as follows:

We provide a breather cap and/or closed crankcase ventilating system. The cap is adapted to be mounted on the fill tube of an internal combustion engine. As is known, the fill tube is used to supply oil to the crankcase of the engine and the tube itself is in direct contact with the crankcase. Such breather caps in the past have been provided with a filtering material so that the air, either drawn into or forced out of the crankcase, will be properly filtered. Where a slight vacuum exists in the crankcase, air will be drawn in and it is desirable that foreign matters and impurities be removed.

In recent years, the smog problem in and around a number of cities has caused extensive work to be done in the development and design of crankcase ventilating for preventing the gaseous contents of crankcases from being exhausted directly into the atmosphere. For example, attention is directed to copending application U.S. Patent No. 3,105,477, issued October 1, 1963, in the name of Wilfred W. Lowther. It is very desirable that such systems be closed, meaning that there is no opportunity or outlet whereby the crankcase vapors may escape, but must go through the return tube to the air cleaner or carburetor, as the case may be, so that they will again go back through the combustion cycle in the engine. Since the vast majority of the crankcase vapor is made up of blow-by, this problem is most serious at high speeds where the pressures developed in the cylinders are the greatest.

When the crankcase is pressurized, meaning that the pressure in the crankcase is greater than atmospheric, the vapors in the crankcase will tend to flow back through the fill tube and breather cap. Under certain circum-

stances, it is very desirable that all of the crankcase vapors be forced to go back through the return tube and valve mechanism to the intake.

The breather cap shown in the present application has the advantage that the check valve will automatically prevent reverse flow and will thereby allow or cause the crankcase to be pressurized. This has the advantage that with the creation of a positive pressure in the crankcase, a pressure over and above atmospheric, the maximum amount of crankcase vapors will go back through the return tube to the inlet since the pressure differential existing between the crankcase and the inlet manifold will be at the greatest. The tension in the spring and the port diameter should be properly calibrated to the inlet flow requirements when a slight vacuum will exist in the crankcase, which is to say that the spring should be comparatively weak so that it overcomes the weight of the valve disk but not a great deal more. It is not desired that the crankcase restrict the inflow of air when a vacuum exists in the crankcase. The present breather cap with the check valve built directly and integrally into it has the advantage that it can be used on after market automobiles, meaning cars that are already on the road, and it is desired to switch them to a closed crankcase system. Also, such a combination breather cap will function as well if not better than units in which the check valve is built integrally into the crankcase or fill tube and in all cases is much easier to change or replace and service.

While we have shown the preferred form and suggested several modifications of our invention, it should be understood that suitable additional modifications, changes, substitutions and alterations may be made without departing from the invention's fundamental theme.

We claim:

1. In a breather cap adapted to be mounted on the

fill tube of an internal combustion engine, a cap type housing having an exterior and interior closed at one end and open at the other and defining a generally annular filter space, inlet openings defined at the lower end of the filter space and an outlet opening defined generally in the center of the interior within the filter space, and a check valve mounted on the outlet within the filter space to provide for the free flow of air into the fill tube but preventing the reverse flow of crankcase vapors out of the fill tube.

2. In a breather cap adapted to be mounted on the fill tube of an internal combustion engine, a cap type housing having an exterior and interior closed at one end and open at the other and defining a generally annular filter space, inlet openings defined at the lower end of the filter space and an outlet opening defined generally in the center of the interior, and a check valve mounted on the outlet to provide for the free flow of air into the fill tube but preventing the reverse flow of crankcase vapors out of the fill tube, a bail mounted on the outlet opening with a central annular portion defining a spring seat disposed away from the outlet opening, a coil spring mounted in the seat, a flexible valve disk biased by the spring toward the outlet opening, and an annular seat formed around the outlet opening of a diameter no greater than the outside diameter of the disk.

3. The structure of claim 2 further characterized in that the seat is in the form of a continuous annular bead projecting toward the disk.
